GOLF TEE

Lester Stewart Barr, Washington, D. C.

Application December 9, 1937, Serial No. 179,006

5 Claims. (Cl. 273—33)

This invention relates to golf tees and more particularly to an improvement in such tees having associated therewith a device designed to help the player hit the proper spot on the ball when driving.

It has been proposed to provide golf tees with an indicating spot positioned to be visible, to the player when addressing the ball, just in back of the ball with respect to the line of flight. The player in looking at this spot is thus caused to gaze at the back portion of the ball which materially aids in correctly hitting the ball.

It is the principal object of the present invention to provide an improved tee of this type which may be easily collapsed for packing, and carrying by the player.

A further object is to provide means to positively control the height of the ball supporting surface of the tee with respect to the ground.

To these ends, the invention includes a golf tee having a target pivoted thereto to swing from a position perpendicular to the pin axis to a position substantially parallel thereto, the target when in perpendicular position being visible to the player when addressing the ball on the tee, just in back of the ball with respect to the line of flight.

Other objects and features of novelty will be apparent from the description taken in connection with the accompanying drawing, in which

Fig. 1 is a side elevation of one embodiment of the present invention showing a ball resting on the tee;

Fig. 2 is a top plan view of the tee shown in Fig. 1;

Fig. 3 is a sectional view taken substantially on line 3—3 of Fig. 1 and looking in the direction indicated by the arrows;

Fig. 4 is a side elevation of the tee shown in Fig. 1, but illustrating the target in collapsed or retracted position; and

Fig. 5 is a sectional view taken substantially on the line 5—5 of Fig. 2 and looking in the direction indicated by the arrows.

Referring to the drawing which illustrate one embodiment of the invention, the tee comprises a pin portion 10 having one end 11 pointed, and the other end 12 enlarged and formed with a concave seat 13 for a ball 14.

The tee is provided with a target 15 mounted to lie in the horizontal position shown in Fig. 1 or to be swung to the collapsed position shown in Fig. 4. One method of accomplishing this consists in providing the pin with a bore 16 intermediate its ends, the axes of the bore and pin

intersecting at right angles. A wire is now inserted through the bore and bent to a substantially U-shape forming the arms 17 and the bight 18. The target 15 is mounted on the free ends of the arms 17. As shown in Fig. 5 this target may consist of thin sheet material having two opposite marginal portions crimped around the free ends of the arm 17 as shown at 19 and 20.

The dimensions of the arms and target are such that when the target is in the horizontal position shown in Fig. 1, it is visible to the player when addressing the ball, lying just in rear of the back of the ball with respect to the line of flight indicated by the arrow 21. The line of sight of the player when addressing the ball is indicated by the arrow 22 of Fig. 1. Thus it will be seen that the target is positioned so that it is spaced from the axis of the pin a distance slightly greater than the radius of the golf ball, that is to say, the central part of the portion of the target visible to the player is thus positioned.

With the target shaped and arranged as shown, the axis of bore 16 is positioned with respect to the point 11 of the pin a distance slightly less than the distance from said bore axis to the inner edge 23 of the target, so that the target may be swung to the position shown in Fig. 4 with the target lying substantially parallel to a plane containing the axis of the pin. The U-shaped member with the target attached thereto acts to limit the amount the pin may be inserted in the ground, thereby positively controlling the height of the ball supporting surface of the tee with respect to the ground.

With the arrangement described herein, the target may be collapsed to the position shown in Fig. 4 so that the tees may be packed in boxes of the usual size provided for their sale, and also carried by the player in his customary manner. In other words, the target, when in collapsed position, does not interfere with packing or carrying the tee.

In operation, the target 15 is swung from its collapsed position to the position shown in Fig. 1 and the tee point 11 inserted in the ground until the target rests on the surface thereof. The ball 14 is placed on the tee and the player takes his stance looking at the target 15 while making the driving stroke.

Of course the target 15 is colored to make it easily seen by the player when addressing the ball. For instance, it may be colored yellow or red.

Although one embodiment of the invention has

been described in detail, it is to be understood that it is not thus limited, but includes modifications and changes that come within the scope of the appended claims.

5. Having thus described the invention, what is claimed as new and desired to be secured by Letters Patent is:

1. A golf tee including in combination, a pin having one end pointed and the other enlarged 10 and formed with a seat for a golf ball, a target pivoted to said pin for movement from a position perpendicular to the axis of said pin to a position substantially in the plane containing said axis, and the outer portion of said target being spaced 15 from said axis a distance slightly greater than the radius of a golf ball.

2. A golf tee including a pin adapted to be inserted in the ground, a target pivoted on said pin for movement from a position perpendicular 20 to the pin axis to a position substantially parallel thereto, the axis of the target pivot intersecting the pin axis, and the target being at such distance from the pin, that, when in a position perpendicular to the axis of the pin, it is visible to 25 the player when addressing the ball, lying just back of the ball with respect to its line of flight.

3. The combination with the pin of a golf tee,

of an arm pivoted thereto intermediate its ends having a target at its free end spaced from the pin axis a distance slightly greater than the radius of a golf ball, said arm being movable from a position perpendicular to the pin axis where the target is visible to a player addressing a ball on the tee, to a position substantially parallel thereto. 5

4. In combination with the pin of a golf tee, a target visible at the back of the ball to a player when addressing the same, and means 10 pivotally supporting said target on the pin for movement from a position perpendicular to the pin axis to a position substantially parallel thereto, the pin and pivot axes intersecting at right angles. 15

5. The combination with the pin of a golf tee having a bore therethrough perpendicular to the pin axis and intermediate its ends, a substantially U-shaped member having its bight disposed in said bore, a target on the free ends of 20 said member, the target being visible at the back of the ball to a player when addressing the ball, and rotatable about the bore axis from such position to a position substantially in a plane containing the pin axis. 25
